[57] CLAIM

The ornamental design for a football training aid, as shown and described.

DESCRIPTION

FIG. 1 is a front elevational view of a football training aid, showing my new design;

FIG. 2 is a rear elevational view thereof showing the tackling dummies in phantom line, the tackling dummies are shown in broken lines for illustrative purposes only;

FIG. 3 is a left side view thereof, the right side view being a mirror image thereof;

FIG. 4 is a top plan view thereof;

FIG. 5 is a bottom plan view thereof; and

FIG. 6 is a perspective view thereof as viewed from the left side and to a reduced scale, with the broken line showing of a tackling dummy in an exploded position for clarity of illustration.

The characteristic feature of my new design resides in the inwardly directed non-overlapping resistor arms in combination with substantially straight skid arms.
